UNITED STATES PATENT OFFICE

2,529,939

RAFTER GAUGE

Ray C. Higgins, Charleston, Ill.

Application May 14, 1948, Serial No. 27,052

2 Claims. (Cl. 33—97)

1

This invention relates to novel and useful improvements in implements for use in carpentry work.

An object of this invention is to determine various angles to be cut in lumber in an improved, facile and dependable manner.

Another object of this invention is to obviate use of mathematical calculations in arriving at the value of angularity to be cut in building construction components particularly in building irregular shapes such as used in gables, roofs and the like.

Another object of this invention is to provide an extremely simplified device of the character described which is inexpensive and dependable.

Ancillary objects and features of novelty will become apparent to those skilled in the art, in following the description of the preferred form of the invention, illustrated in the accompanying drawings, wherein;

Figure 1 is a plan view of the preferred form of the invention, showing a piece of lumber in phantom applied thereto;

Figure 2 is a sectional view illustrating details of construction taken on the line 2—2 of Figure 1 in the direction of the arrows;

Figure 3 is a sectional view taken on the line 3—3 of Figure 1;

Figure 4 is a fragmentary elevational view showing a second use of the invention, and;

Figure 5 is a fragmentary elevational view showing a further use of the invention.

This invention has been developed in order to provide a device for easily cutting angles in lumber in building houses, stores, buildings of all descriptions. Of prime importance is the utility of the present invention when various and sundry values of angles must be determined and cut.

The instant rafter gauge includes a bottom 10 and top 12 rail with slots 14 and 16 respectively extending longitudinally thereof. A first side 18 is rigidly attached at its ends to a pair of ends of the said top and bottom 10 and 12 respectively. A second side 20 is attached at one end to the said top 12 and attached to the bottom 10 adjacent but not at the opposite end. Accordingly, a portion of the said side 20 projects below the said bottom 10. A slot 22 is provided in the side 20 and terminates in the projecting portion thereof.

Graduations are supplied on the top and bottom, preferably graduated in feet and inches. Also, graduations are supplied on the said side 20 for a purpose to be described subsequently.

An intermediate rail 24 extends between the

top and bottom 10 and 12 respectively and is attached at each end by means of set screws 26 which project through the slots 14 and 16 and a suitable aperture in the intermediate rail 24. A suitable wing nut 28 or the like may be attached to the screw 26 in order to form a readily loosened fastening means thereby rendering the intermediate rail 24 adjustable longitudinally of the top and bottom rails.

10 A slide 30 having a slot 32 extending longitudinally thereof is provided and this slide has graduations thereon. The said slide is attached to the side 20 by means of a screw 36 having a wing nut 38 detachably secured thereto. Thus, 15 the slide is adjustably positioned within the confines of the slot 22.

The said intermediate rail 24 may have the indicia bearing section thereof raised slightly if it is found desirable from the graduation bearing portion in order that the tip of the slide may be moved in a straight line longitudinally of the intermediate rail 24.

In operation a piece of lumber 40 is used in association with the device as is seen in Figure 25 1 in order to cut a desired notch at the proper angle. The desired height in the gable or other portion of the roof is found in the intermediate rail and in this instance it is 5. The end of the slide is placed at 5. The base of the gable is 30 determined by measurement from the side 20 and the intermediate rail take out both the top and the bottom graduations in order that the device be square. Then, the length of rafter may be measured directly from the slide 30 and a 35 notch indicated as seen at A in Figure 1.

In determining other requisite angles, such as B in Figure 5, the rafter 40 may be turned on edge and the angle marked (by a pencil or other suitable scribe) between the sides defining the 40 angle B.

Of course, for various considerations such as the desired pitch, the slide 30 may be raised in the slot 22 by means of the screw 36 riding in the elongated aperture 32 and the slot 22 in order 45 to determine at what pitch the roof or gable is to be made.

It is understood that the above described uses of the invention are for illustrative purposes only and the invention may be subjected to use in determining and cutting various and sundry desired angles in the building trade.

While there has been described and illustrated but a preferred form of the invention, it is apparent that variations may be made without departing from the spirit thereof.

Having described the invention, what is claimed as new is:

1. A rafter gauge comprising a bottom rail and a top rail having slots, a first side rigidly attached to said bottom and top rails, a second side having a slot and graduations, said second side being attached at one end to said top rail and projecting below said bottom rail, the slot in said second side projecting below said bottom rail, an intermediate rail, means for attaching said intermediate rail to said top and bottom rail, said top and bottom rails having graduations thereon, a slide having an elongated aperture, and means adjustably attaching said slide to the second side.

2. A rafter gauge comprising a bottom rail and a top rail having slots, a first side rigidly attached to said bottom and top rails, a second side having a slot and graduations, said second side being attached at one end to said top rail and projecting below said bottom rail, the slot in said second side projecting below said bottom rail,

5 an intermediate rail, means for attaching said intermediate rail to said top and bottom rails, said top and bottom rails having graduations thereon, a slide having an elongated aperture, means for adjustably attaching said slide to the second side, and said attaching means including threaded members having nuts thereon.

RAY C. HIGGINS.
